UNITED STATES PATENT OFFICE.

EMMIT G. LATTA, OF SYRACUSE, NEW YORK, ASSIGNOR TO CORONA TYPEWRITER COMPANY, INC., A CORPORATION OF NEW YORK.

TYPE-WRITING MACHINE.

1,261,823.

Specification of Letters Patent. Patented Apr. 9, 1918.

Application filed June 3, 1915. Serial No. 31,873.

To all whom it may concern:

Be it known that I, EMMIT G. LATTA, a citizen of the United States, residing at Syracuse, in the county of Onondaga and State of New York, have invented a new and useful Improvement in Type-Writing Machines, of which the following is a specification.

This invention relates to improvements in typewriting machines and has for its objects to produce a key lever action for typewriting machines that will produce an accelerating motion in the type bars; that will be simple and easy to operate; that has a uniform depression of the several keys, and particularly one that is adapted for use in machines in which the type-bar segment is set very close to the base line of the machine or surface on which it rests. Another special object is to adapt the key lever system for use in a machine in which the type-bar segment is shiftable to enable a plurality of type on each bar to print on the same line. The invention is herein shown as applied to a collapsible typewriting machine, such as disclosed in my pending application Serial No. 658,153, filed November 2, 1911, to which it is particularly adapted, and since the general construction of the two machines may be alike, I have shown in the drawings in this application only such parts as are required to make the invention clear.

In the accompanying drawings:

Figure 1 is a plan of the keyboard and segment, with one of the central type-bars in place, and showing the shift frame and front end of the two part collapsible main frame.

Fig. 2 is a longitudinal section on line 2-2, Fig. 1.

Fig. 3 is a transverse section on line 3-3, Fig. 1, showing the segment in elevation.

Fig. 4 is a side elevation of the shift frame detached.

Fig. 5 is a longitudinal section on line 5-5, Figs. 1 and 3, showing one of the outer sub-levers and key levers connected thereto, and one of the links that connects the sub-lever to the type-bar.

Fig. 6 is a side elevation showing a modification.

A and B represent the two parts of the collapsible main frame which are pivotally connected at the front corners, as shown at a in section at the right in Fig. 1, and C is a

shift frame pivotally connected to the frame B at c' and c². The pivots a a connecting the frame parts A B, may be of any suitable construction, as the frame is collapsed but seldom, but adjustable cone pivots are 60 preferably employed for the shift frame. The shift frame is preferably of the form shown in Figs. 1, 2 and 4. It comprises two side bars and rear end bar c³ with integral flat cross bar c⁴, and the rigidly connected 65 front cross bar c⁵. A roller D, shown in Fig. 1, is connected to a projection d on one end of the shift frame, and the shift keys d' d² actuate a pair of cams (not shown) which act on this roller to move the shift 70 frame up and down from the position shown to change the case as desired. Any other suitable means may, however, be employed for shifting the shift frame.

The type-bar segment E is preferably 75 slotted to receive the type-bars F, and a curved wire e shown serves as a pivot for the whole series of type-bars. The segment can be secured to or formed with the shift frame in any suitable way.

The key levers G G' G² are arranged in three banks or lengths of slightly different form, but all are of the same order, differing to adapt them to swing type-bars that swing in planes radial to the printing point, and to equalize the dip of the keys. Fig. 2 shows the three different forms used for all the key levers except a few, preferably four, at each end of the keyboard. All the key levers have a rocking fulcrum on the plate 80 c⁴ of the shift frame, and the rocking part of the levers differ slightly in length and curvature, as seen at g g' g², Fig. 2. The plate c⁴ of the shift frame, as shown, is planed off smooth and flat where the key 85 levers rock on it, except that a rib H projects upwardly from the plate between its front and rear edges, and this rib is slotted, as seen in Figs. 1, 2 and 5, for the key levers, the bottom of the slots being flush with 90 the upper surface of the plate c⁴ so that the levers rock on the top surface of the plate, the same as if it were a plain flat surface.

The slotted rib H acts to hold the key levers against lateral displacement, and each of the 95 levers has a small opening i, as shown in Fig. 2, through which a wire K passes. The openings are only slightly larger than the wire and serve to prevent the levers from creeping, as those in the central part of the 100 105 110

keyboard would otherwise do. The openings *i* in the levers need only be large enough to permit the necessary vertical movement of the levers, which is slight at this point.

As shown in Fig. 1, the wire *K* does not project into the four key levers at each end of the keyboard, because those levers are held against endwise movement by being pivotally connected to bell crank levers which in turn are pivotally connected to the rear edge of the plate *c*⁴ of the shift frame. Each of the levers in the central part of the keyboard is connected at its rear end directly to one of the type-bars by a link *l*, as shown in Figs. 2 and 3, and a helical spring *m* connecting each key lever to the rear of a plate *m'* acts to restore the key lever and the connected type-bar to normal position. Screws *m*² passing through the front edge of the plate *m'* into the plate *c*⁴ act to increase the tension of the whole series of springs *m* by rocking the plate *m'* over the rear edge of the plate *c*⁴. The four key levers at each end of the keyboard are connected to their companion type-bars by means of the aforesaid bell crank sub-levers, as shown at *N*, Figs. 1, 3 and 5. The sub-levers *N* are preferably pivotally mounted in a slotted part *n'* projecting rearwardly from the plate *c*⁴ of the shift frame, as shown in Figs. 1 and 5. For the key levers that actuate the sub-levers, return springs *n'* are used, connected to a short plate *n*² and acting on the links *n* to return the type-bars, sub-levers and connected key levers to normal position, as shown in Fig. 5. As shown in Fig. 3, about twelve type-bars at each side of the center of the segment are all that can be actuated properly by a direct link connection, like *l*, owing to the increasing angle of the radial planes that the type-bars move in, but by the use of bell crank sub-levers *N* with the links *n* connecting them to the type-bars, similar rocking key levers act on the type-bars with a pull instead of a push, as with the direct link connection *l* described. By this means a vertical and substantially uniform action of the whole keyboard is secured.

By the use of the links *l* connecting the central key levers directly to their type-bars it is possible to locate the type-bar segment very low down, as shown in Figs. 2 and 3, and the upward curve of the ends of the segment permits the ends of the outer key levers and their sub-levers to project rearwardly under these end portions of the segment.

The upright links *l* connecting the centrally located type-bars directly to their key levers are of graduated lengths to compensate for the curve of the segment, and

the key levers at the sides of the keyboard which are connected to the sub-levers are made with variable rocking surfaces similar to those seen in Fig. 2, to equalize the action of these levers which are of different lengths, 70 both as to their front and rear arms, as shown in Fig. 1.

As shown in Fig. 1, the keyboard is considerably wider than the type-bar segment and the key levers converge from the front 75 to the rear of the keyboard, and all but three of them, on straight lines. To avoid excessive divergence forwardly from the sub-levers the lower arms of the sub-levers are offset, as shown in Fig. 1, and their 80 pivots are located in vertical planes about half way between the planes of the links *n* and rear ends of the key levers. The upper arms of the sub-levers are bent inwardly toward the center of the segment 85 about as much as their lower arms are bent outwardly from the plane of their pivots. The rear ends of the key levers curve upwardly to make room for the lower ends of the adjacent sub-levers to swing upward 90 without interference, and a similar curve in the key levers in the central part of the keyboard makes room for the retracting springs *m*.

The pivotal connections between the key 95 levers and bell crank sub-levers are located so as to swing upwardly and forwardly, as shown in Figs. 5 and 6. This is because the curved edges of the key levers that rock on their fulcrum naturally roll or creep forwardly as the keys descend, and this location of the pivots permits such forward movement without objectionable sliding friction. The slots in the key levers, shown in Fig. 2, for the wire *K* could be curved for 100 the same reason, but as the levers having such slots have less inertia to overcome and require slightly less force to actuate them, it is not necessary to incur the extra expense of curving these slots. As shown, the two 105 different connections between the key levers and type-bars require almost exactly the same force, and less than a three ounce weight on the key will throw any one of the type-bars to the printing point. 110

The type-bars are of two different forms, as shown in Figs. 2 and 5, to adapt them to the two different forms of connecting links.

The key levers pass through the rib *H* on diagonal lines and the lever slots in the rib could be made on the same angles as the key levers, but to facilitate manufacture it is preferred to make the slots at right angles to the rib, and wide enough for one end of one side of the slot to form a guide for one 120 side of its key lever and the other end of the opposite side of the slot to guide the other side of the key lever, as indicated at the left in Fig. 1. This permits all of the 125 slots to be machined simultaneously by 130

having a mandrel with cutters of suitable widths.

It will be seen that the keyboard shifts with the segment and produces an acceleration of motion in the type-bars by rocking key levers. By rocking the key levers on the shift frame the rocking contact can be made long enough to produce the best results, and by the described connections of the key levers to the type-bars the key levers can move up and down in vertical planes instead of in radial planes, thus making the action of all key levers uniform.

The modified arrangement of the sublever O shown in Fig. 6, is suitable for use in machines of ordinary height and in machines in which the keyboard does not shift. This permits the key levers to extend farther to the rear. They rock on a fixed part of the main frame and, like those previously described, produce an acceleration of motion in the type-bars, with a uniform movement of the keys.

While the key levers are shown as having curved edges rocking on a flat surface, this could be reversed, and the key levers made with straight edges to rock on a curved surface, or both parts may be curved, and the same result produced.

P represents a back stop for the type-bars. This is supported by the front rod c^5 of the shift frame to which it is connected by braces p' and p^2 . This back stop shifts with the shift frame, but it is so near the pivot that its movement is slight. Q represents the comb that separates the key levers at their front ends, and R is a strip of felt which forms the back stop for the key levers.

I claim as my invention:

1. In a visible typewriting machine, the combination of a segment, a series of type bars pivotally held to said segment, a keyboard having key-operated levers, one for each type bar, links connecting the intermediate key-operated levers to certain of the type bars, and bell-crank levers connecting other and outer levers to other type bars.

2. In a typewriting machine, the combination of a segment, a series of upwardly and rearwardly moving type bars pivotally held to said segment, a support, and a keyboard having key-operated levers provided with an extended rocking connection with said support, one for each type bar, links connecting the key-operated levers to certain of the type bars, and bell-crank levers connecting other levers to other type bars.

3. In a typewriting machine, the combination of a series of type bars that swing upwardly and rearwardly, a normally fixed fulcrum plate, and a series of key-operated levers operatively connected to the type bars, one for each type bar, having a rocking connection with said fulcrum plate inter-

mediate the ends thereof, and means for guiding and holding said levers at a point to adapt the key-operated levers to rock on opposite sides of said holding means, said holding means comprising a slotted rib and a rod held in said rib.

4. In a typewriting machine, the combination of a series of type bars, a fulcrum plate having a slotted rib crosswise thereof, a rod held to said rib, and a series of key-operated levers each having a slot through which the rod passes and guided in the slots of said rib, said key-operated levers having a curved lower edge adapted to rock directly upon the fulcrum plate, and means operatively connecting the key-operated levers to the type bars.

5. In a typewriting machine, the combination of a series of type bars, a fulcrum plate having a slotted rib crosswise thereof, a rod held to said rib, and a series of key-operated levers each having a slot through which the rod passes and guided in the slots of said rib, said key-operated levers having a curved lower edge adapted to rock directly upon the fulcrum plate on opposite sides of said rod and rib, and means operatively connecting the key-operated levers to the type bars.

6. In a typewriting machine, the combination of a series of type bars, a segment to which the type bars are pivoted, a fulcrum plate, a keyboard comprising a number of key-operated levers having a rocking connection directly on said plate and extending on both sides thereof, links connecting certain of said levers to the type bars, bell-crank levers having vertically extending and horizontally arranged arms located at the ends of the keyboard and pivotally held at the rear edge of said fulcrum plate and connected to the end key-operated levers and their type bars, and means for holding the key-operated levers against substantial creeping action.

7. In a typewriting machine, the combination of a series of type bars, a segment to which the type bars are pivoted, a fulcrum plate, a keyboard comprising a number of key-operated levers having a rocking connection directly with said plate and extending on both sides thereof, links connecting certain of said levers to the type bars, and bell-crank levers located at the ends of the keyboard and pivotally held at the rear edge of said fulcrum plate and connected to the end key-operated levers and their type bars.

8. In a typewriting machine, the combination of an upwardly and rearwardly swinging type-bar, a key lever extending forwardly and outwardly from a point adjacent to the pivoted end of the type-bar, a bell crank sub-lever having an upright arm operatively connected to the type-bar and a horizontal arm pivotally connected to the

4
rear end of the key lever, and a fulcrum for the intermediate part of the key lever over which it moves with a constantly changing contact.

- 5 9. In a typewriting machine, the combination of an upwardly and rearwardly swinging type-bar, a key lever extending forwardly from a point substantially under the pivoted end of the type-bar, a bell crank
10 sub-lever having an upright arm operatively connected to the type-bar and an offset substantially horizontal arm pivotally connected to the rear end of the key lever, and a fulcrum over which the central part of the
15 key lever moves with a longitudinally shifting contact.
10. In a typewriting machine, the combination of an upwardly and rearwardly swinging type-bar, a key lever extending forwardly from a point substantially under the pivoted end of the type-bar, a bell crank
20 sub-lever having an upright arm with its upper end arranged substantially in the radial plane of the type-bar and operatively
25 connected thereto and a substantially horizontal arm pivotally connected to the rear end of the key lever, and a fulcrum for the key lever over which its intermediate part moves with a longitudinally shifting contact.
- 30 11. In a typewriting machine, the combination of an upwardly and rearwardly swinging type-bar, a key lever extending forwardly and outwardly from a point sub-
35 stantially under the pivoted end of the type-bar, a bell crank sub-lever having a substantially horizontal arm offset and pivoted to the rear end of the key lever and an upright

arm having its end arranged substantially on the radial plane of the type-bar, and a 40 fulcrum over which the intermediate part of the key lever moves with a longitudinally shifting contact.

12. In a typewriting machine, the combination of a series of upwardly and rear- 45 wardly swinging type-bars, a series of key levers extending forwardly from points substantially under the pivoted ends of the type-bars, a series of bell crank sub-levers of graduated lengths operatively connected to 50 the type-bars and to the rear ends of the key levers, and a fulcrum over which the intermediate parts of the key levers move with a longitudinally shifting contact.

13. In a typewriting machine, the combination of a series of upwardly and rearwardly swinging type-bars, a series of key levers extending forwardly from a point substantially under the pivoted ends of the type-bars, a fulcrum for the key levers over 60 which their intermediate parts move with a longitudinally shifting contact, a series of bell crank sub-levers having upwardly extending arms operatively connected to the type-bars, and substantially horizontal arms 65 pivotally connected to the rear ends of the key levers at points that swing upwardly and forwardly as the key levers rock on their fulcrums.

Witness my hand this 1st day of June, 70
1915.

EMMIT G. LATTA.
